[57] **CLAIM**

The ornamental design for a device for baiting fish hooks, substantially as shown.

DESCRIPTION

FIG. 1 is a front elevation view of a device for baiting fish hooks showing my new design, the rear side being a reverse image thereof;

FIG. 2 is an elevation view showing the left side thereof as seen in FIG. 1;

FIG. 3 is a side elevation view showing the opposite side thereof;

FIG. 4 is a top plan view thereof; and

FIG. 5 is a bottom plan view thereof.

FIG.1

FIG.2

FIG.3

FIG.4

FIG.5
